UNITED STATES PATENT OFFICE

LESLIE DANA, OF ST. LOUIS, MISSOURI, ASSIGNOR TO CHARTER OAK STOVE & RANGE COMPANY, A CORPORATION OF MISSOURI

STOVE CONSTRUCTION

Original application filed April 4, 1928, Serial No. 267,401. Divided and this application filed October 21, 1929, Serial No. 401,162.

This invention aims to improve stream-line and other cooking ranges, particularly as respects the fire box and grate and shaker structures thereof. Further objects of the invention are to provide a duplex grate suitable for burning either coal or wood and to provide a strong, simple stove structure capable of easy assembly.

Other objects and advantages of my invention will be apparent from the following specification and accompanying drawings of a preferred embodiment illustrating the principles thereof, wherein the same reference characters apply to the same elements in all figures, and wherein:

Fig. 1 is an isometric view showing a portion of the fire box end wall and adjacent portions of the front and top of a stove embodying my invention, certain parts being removed for better illustration;

Fig. 2 is a sectional elevation taken through the fire box at line 2—2 of Fig. 3;

Fig. 3 is a sectional elevation taken on line 3—3 of Figs. 2 and 5;

Fig. 4 is an isometric view of the grate and operating parts removed from the fire box; and

Fig. 5 is a sectional plan view taken on line 5—5 of Fig. 3.

Some idea of the general appearance of the fire box end of a stove illustrating the invention may be discerned in Fig. 1, and the internal arrangement and construction is best seen in Figs. 2 through 4.

The drawings show the fire box of a cooking range of the type having at one end a fire box 11 and ashpit 12, together constituting the combustion chamber, separated by a shaking grate comprising a plurality of bars 13, 13, and an oven 14 adjacent thereto, around which the products of combustion may circulate, surmounted by a flat top 15 of convenient design having a plurality of removable rectangular plates 16 and round lids 17 and supported on a base.

For convenience I herein show and describe the fire box as at the left end of the stove, which is usual in the art.

The external casing comprises the top 15, four side or end walls and a bottom, all fitted

to each other by concealed flanges and bolted together interiorly, making externally flush joints. Each of the plate members will ordinarily be an integral casting. The exposed surface of the casing may be enamelled, except for the top 15, which is usually of smooth black or polished finish, with a quarter-round edge rail, preferably polished to match. The bottom and back, which are ordinarily concealed from view, may be of rough black

all connecting elements, such as bolt heads, lugs and so on, pertaining to the front and ends are arranged not to protrude through or be visible on the outside, all door hinges and latches are concealed, and all handles and knobs are made as inconspicuous as possible, the principal ones being cast integral with the parts to which they apply, and exteriorly stream-lined so that the visible surface will be almost entirely free from projections, thus resembling in appearance a single polished block of enamel.

To enhance the artistic effect and carry out the unitary appearance, the left end 22 and front 23 of the casing are swelled outward and in again from bottom to top, and the extreme top portion 19 is molded out on a curve of shorter radius, meeting the bottom of the quarter-round top rail 18 so as to form therewith a smoothly rounded top edge without overhang or irregularity. The upright edges or corners 20 of the casing are likewise curved vertically and rounded to carry out the effect.

Since the appearance of the back 24 of the stove is of little importance, no attempt is made to stream-line it. Consequently, in order to finish the left end 22 in an artistic manner and avoid an unsightly junction between the irregular back 24 and the smoothly curved left end, a finishing piece 25 (see Fig. 1) is secured along the rear upright edge of the left end. The top of this piece is relatively wide, as at 26, and the bottom narrow, as at 27, to conform to the difference in width of the stove at top and bottom, as will be understood by reference to Fig. 3 of this application and to my copending application Serial No. 267,401, filed Apr. 4, 1928, of

which this application is a division. This piece 25 is suitably molded to the characteristic configuration of the left end and is vertically grooved, as at 28, and apertured, to receive pivot ears 29 and 30, to permit the mounting and operation of a grate shaker handle 31 described below.

The horizontally pivoted fire box door 35 (see Figs. 1 and 3), on account of the heat to which it is exposed, has as its principal element a cast iron liner 38, partially curved to follow the shape of the stove, the hinges 39 with integral transverse heads 40 being cast thereon, and a latch 41 being riveted thereto. A facing plate 42, conforming to the curvature of the stove, and enamelled, is fastened to the liner by a screw. This plate 42 includes the integral handle 43, which like the handles on the doors 36 and 37, is a curved brow overhanging and concealing an aperture in the door plate thereunder, the brow also being open at the bottom and formed without sharp edges, harmonizing with the graceful flowing curves of the stove body. The recess into which the door 35 fits is formed by flanges 44, with appropriate recesses for hinge and latch engagement, respectively.

On all three doorways the rabbet effect of the concealed flanges 44 of the openings combines with the edges of the doors and liners to make a sufficiently air-tight fit with very little grinding or machining of the castings.

Referring particularly to Figs. 2 and 3, the fire box 11, herein shown as adaptable to burn either wood or coal, carries fluted lining slabs, preferably of cast iron, at front, back and ends, the front and back slabs 45 and 46 having fingers 47 at the bottom to hold the fuel while allowing the access of air. Small holes 48 near the top of the front slab 45 permit a slight ingress of air above the fire. An asbestos backing strip 49 on the front slab 45 cuts down the escape of heat to the outside of the stove.

The front end slab 50 is usually kept in place when burning coal, to save the door 35 from the injurious effects of the coal gases. It is contemplated when burning wood that the slab 50 be removed so that sticks may be thrown in through the door 35.

As clearly shown in Fig. 3, the rear end extension 51 is cut off from the fire box proper by means of the rear end slab 52. A water coil may be located in this space, although such a coil is not a feature of the present invention and is accordingly not illustrated. The usual water pipe holes 53 and pivoted covers 54 are provided.

The grates 13 are of the duplex type, rotatable on trunnions 55 carried in bearings at either end of the fire box. The bearings at the rear consist, respectively, of a pocket 56 and of a hole 57, both in the back plate 24, and those at the front comprise forwardly

extending hooks 58, cast integral with the front plate 23, and covered by a trunnion-retaining cap 59, Fig. 5, (omitted from Fig. 1).

The pocket 56 and hole 57 constituting the rear bearings for the shaker-grates are each sufficiently oversize to permit slight angular movement of the grate bars to enable the front ends of the bars to be moved sideways and downwardly out of engagement with the stationary extending hook-bearings 58 to facilitate removal and replacement of the grate bars. This provision enables the use of rigid hook-bearings 58 cast integral with the front plate 23. The trunnion retaining cap 59 prevents accidental displacement of the grate bars when in use.

Each grate bar is of generally triangular cross section, having only two effective faces, one concave 60, with relatively large rectangular openings 61, and the other convex 62, with smaller elliptical openings 63. Either pair of faces may be used to support the fire, according to the nature of the fuel, the concave faces 60 ordinarily being used for coal and the convex 62 for wood.

Shaking of the grate, or change of the faces used, is accomplished by the lever 31 permanently mounted on the left end of the stove, the handle of said lever extending above and slightly away from the stove top 15 so as to remain cool.

The lever 31 is fulcrumed to a lug 64, Fig. 4, cast on the rear end lining slab 52 of the fire box 11, which lug projects through the apertured groove 28 in the finishing piece 27 (Fig. 1). Referring particularly to Fig. 4, the lower end of said lever is connected by a link 65 to an arm 66 secured to the rear end of one of the grate trunnions 55 which extends out through the hole 57 in the back plate 24. The two grate bars 13 are interconnected by segmental gears 67, at their front ends so as to oscillate in unison when the lever 31 is shaken.

An apron 68 positioned beneath the grates and extending around three sides of the fire box directs falling ashes into the ashpan.

What I claim is:

1. In a stove, in combination, a narrow elongated fire box, a pair of grate bars longitudinally disposed oscillatable therein, end trunnions on said bars, bearings for said trunnions comprising, adjacent one end of said fire box, two stationary hook shaped bearings depending from the body of said stove, and a detachable cap piece having recesses for engaging one end of each of said trunnions to hold the same in place in said bearings, and bearings for said trunnions adjacent the opposite end of said fire box comprising one recess in the body of said stove and one aperture in said body, said recess and said aperture permitting slight angular displacement of their respective trunnions.

2. In a stove, in combination, a fire box, a pair of shaker grates mounted therein and interconnected for conjoint action, a fire box lining slab forming the rear end of said fire box and having a portion extending laterally outside of said fire box, an upwardly extending lever pivoted to said portion and having a handle portion extending away from said fire box to be protected from the heat thereof, and means interconnecting said lever and grates whereby operation of said lever will cause movement of said grates.

3. In a stove, in combination, a fire box, a pair of shaker grates mounted therein and interconnected for conjoint action, a fire box lining slab forming one wall of said fire box and provided with a fulcrum point, and shaker means connected to said grates and fulcrumed to the fulcrum point of said lining slab.

In testimony whereof, I have signed my name to this specification.

LESLIE DANA.
